United States Patent Office

Des. 220,692
Patented May 11, 1971

220,692

MODULE EXTENDER

Ira Morris, Framingham, Mass. (6% Digital Equipment Corp., 146 Main St., Maynard, Mass. 01754)

Filed Apr. 27, 1970, Ser. No. 22,653

Term of patent 14 years

Int. Cl. D13—99

U.S. Cl. D26—1

FIG. 1 is a front perspective view of a module extender embodying my new design;

FIG. 2 is a similar view from the rear thereof;

FIG. 3 is an end view thereof; and

FIG. 4 is a view of the other end.

I claim:

The ornamental design for a module extender, substantially as shown.
